JOHN FARRAR AND WILLIAM GROVES, OF PROVIDENCE, RHODE ISLAND.

Letters Patent No. 67,181, dated July 30, 1867.

IMPROVEMENT IN MOULDS FOR CASTING METAL.

The Schedule referred to in these Letters Patent and making part of the same.

TO ALL WHOM IT MAY CONCERN:

Be it known that we, JOHN FARRAR and WILLIAM GROVES, of Providence, in the county of Providence, and State of Rhode Island, have invented an Improvement in Flasks for Casting Pipes and other similar articles; and do hereby declare that the following is a full and exact description, reference being had to the accompanying drawings, making a part of this specification.

The nature of our invention consists in making the flasks for casting water pipes and other cylindrical articles in three or more longitudinal sections, and also in an improved lining for such flasks, by means of which their durability is very much increased, and a great number of pipes or other articles may be cast in the same without a renewal of the lining at each casting, as in those now employed.

To enable those skilled in the art to make and use our invention, we will proceed to describe its construction and operation. In the drawing—

Figures 1 and 2 represent cross-sections of the flask, and

Figure 3 a perspective view of a longitudinal section.

The flask is shown as closed in fig. 1, and as opened in fig. 2, the sections A A A, of which it is composed, being hinged together as shown, or otherwise secured when used for casting.

A is the outer case, made of metal, wood, or other suitable material. b b are small openings in the same for the escape of the gases. B is a lining, about three-eighths of an inch thick, composed of moulding-sand, coarse gravel, and broken ciuders, mixed to a paste with clay-water, and applied as shown in the drawing, filling the orifices b b, which serves to keep this lining in place. C is another lining, formed of finer materials. We prefer about two parts of burnt clay pulverized, with one part of plumbago, to be applied by mixing to a paste with clay-water, and when dry to be well polished with plumbago. The coating C is to be about one-eighth of an inch thick, the two linings B and C being held in place and their edges protected by the flanges or strips a a, which we either make very thin or wedge-shaped, as shown. D is the core, to be used in casting pipes; and E is the tunnel through which the metal is to be poured, which is also lined with the composition previously described.

The arrangement consisting of the outer case A and linings B and C, with the flanges or strips a a, may also be used in a flask of two parts; but there is less danger of damage to the interior lining when made, as shown, in three. Other suitable compositions may be used for either lining.

We claim the combination, in any flask for casting the above-named articles, of the outer case A, the flanges a a, the coarse inner lining B, composed of certain suitable materials, as set forth, and a finer-grained lining, C, composed of another combination of materials, to be mixed and applied substantially as described.

JOHN FARRAR,
WILLIAM GROVES.
